UNITED STATES PATENT OFFICE.

ANDREW P. PAZOWSKI, OF EDMONTON, ALBERTA, CANADA.

BUTTONLESS DRAWERS.

Application filed July 13, 1926, Serial No. 122,230, and in Canada January 4, 1927.

This invention relates to improvements in undergarments and more particularly to an improvement in drawers intended for men's wear, although they may equally as well be worn by boys.

One of the objects of the present invention is to provide a pair of drawers which will be exceptionally comfortable and so formed as to afford firm and yet comfortable support for the abdomen, thus tending to prevent rupture or strains and pains incident to hard labor, horseback riding, walking, running, etc.

Another object of the invention is to provide a pair of men's drawers which will be devoid of the ordinary buttons at the fly and to provide means for closing the fly and for securing the waistband of the garment about the wearer without causing any discomfort.

Another object of the invention is to provide such a garment with a crotch insert providing for a desirable fullness at the back or seat of the garment.

In the accompanying drawings:

Figure 1 is a front elevation of the garment embodying the invention, the garment being closed.

Figure 2 is a similar view of the garment, the garment being open.

Figure 3 is a rear elevation of the garment.

Figure 4 is a detail sectional view taken substantially on the line 4-4 of Figure 1, looking in the direction indicated by the arrows.

Figure 5 is a detail sectional view taken substantially on the line 5-5 of Figure 1, looking in the direction indicated by the arrows.

Figure 6 is a plan view of one of the leg blanks of the garment.

Figure 7 is a similar view of the crotch blank.

The garment embodying the invention comprises the usual body 1 and legs 2 depending therefrom, and, preferably, the garment is made up of two blanks substantially of the form shown in Figure 6 of the drawings, together with the supplemental blank

shown in Figure 7. Except as will presently be explained, the main blanks are of counterpart form and are not materially different from the ordinary blanks except that each is cut away at its rear edge at the portion which is to extend at the rear side

of the crotch of the garment, as indicated by the numeral 3, and in the upper edge of the blank a substantially V-shaped incision 4 is formed which serves a purpose to be presently explained. Above the cut away 60 edge portion 3, the blank is formed with a straight edge portion 5 and, by reference to Figure 6 of the drawings, it will be observed that from the rear upper corner of the blank the upper edge thereof is extended on a 65 downwardly and forwardly curved line which is more pronouncedly curved at its forward portion, as indicated by the numeral 6, so that the front of the garment will, when completed, occupy a position slightly lower 70 than the rear of the garment at the waist thereof, whereby to serve the purpose of properly supporting the abdomen.

Figure 7 of the drawings indicates a triangular crotch blank which is disposed between two of the blanks shown in Figure 6 of the drawings, at the time of manufacture of the garment, and stitches are run along the edges 5 of the blanks shown in Figure 6, and form the back seam 7 of the garment, 75 stitches being likewise run along the opposite inclined edges 8 of the crotch blank of Figure 7, which blank is indicated by the numeral 9, and uniting these edges to the edge portions 3 of the two blanks shown in 80 Figure 6, the apex 10 of the crotch blank 9 being located and secured at the lower end of the back seam 7, as clearly shown in Figure 3 of the drawings. The leg portions 2 of the blanks shown in Figure 6, are fashioned in 85 the usual manner to provide the inner leg seams and thus form the legs of the garment, and stitches are run through the edges of the notches 4 so as to suitably restrict the upper portion of the garment at the rear thereof 90 at opposite sides of the back seam 7, as indicated by the numeral 11 in Figure 3 of the drawings, so as to adapt the garment to 95 conform to the hips. The lower edge 12 of the crotch blank 9 is preferably of the curvilinear form shown in Figure 7 and is 100 united by stitching to inwardly curved edge portions 13 of the blanks shown in Figure 6, located at the front of the said blanks, thus 105 completing the crotch of the garment.

One of the main blanks of the garment has a straight front edge portion indicated by the numeral 14, and the other main blank is provided at its front, as shown in Figure 6, with an integral fly flap 15 having an 110

extended upper end portion 16 projecting initially above the upper edge 6 of the said blank. The fly flap 15 is carried by the body blank which forms the right half of the garment, and the extended upper end 16 thereof is folded upon itself, as indicated by the numeral 20, in a forward direction, and thence back upon the fold, as indicated by the numeral 21, and the three plies thus formed are stitched together along a line 22 which is slightly spaced above the fold line 21, so that a two-ply tab 23 is provided extending longitudinally of the upper edge of the said fly flap 15 and may be displaced 15 in a forward direction with respect to the fly flap, as illustrated in Figure 5 of the drawings, and for a purpose to be presently explained.

The garment is provided at its waist portion with a truss belt which is indicated in general by the numeral 24, and the said belt is preferably formed from a plurality of plies of any cloth or other material found suitable for the purpose, the belt, from 20 points spaced with respect to the fly opening at the front, and throughout its portion which extends about the hips and back of the waist portion of the garment consisting of two plies of material, indicated by the numeral 26, and from these points to the opposite sides of the open front of the garment embodying a third ply 27 interposed between the said plies 26. These plies are all stitched together in any appropriate 25 manner as to be uniformly united throughout their length and are likewise stitched at intervals, as indicated by the numeral 28, to the waist portion of the body of the garment, the belt conforming to the contour of the upper margin of the blanks from which the body of the garment is formed. As clearly shown in Figures 1, 2 and 4 of the drawings, the fly flap 15 is to be arranged in position extending in overlapping relation with respect to the inner side of the front edge portion 14 at the fly opening of the garment. The truss belt 25 terminates at one end portion at the right hand side of the front of the body of the garment or, in 30 other words, that portion from which the fly flap 15 extends, and a buckle, which is indicated in general by the numeral 29, is applied to this end of the said truss belt. The buckle comprises a body plate 30 having a ridge 31 formed transversely thereof near one end, and top and bottom flanges 32 between which and at the said end of the body there is mounted for pivotal movement, a bail 33 having an inwardly turned 35 end portion 34 which may be serrated or toothed and which has frictional or biting engagement with the said end portion of the belt at a point opposite the ridge 31, so that the end of the belt is securely connected 40 with the said buckle and yet, by swinging

the bail 33 about its pivot, the locking portion 34 will be moved away from the belt so as to permit of removal of the buckle from this end of the belt. A similar locking bail 35 is mounted pivotally between the flanges 32 of the buckle near the other end thereof and has a belt engaging tongue 36 which frictionally engages the other end 37 of the belt, which end is inserted between the said tongue 36 and a serrated ridge 38 formed in the body plate of the buckle at the last mentioned end thereof, the said end portion 37 of the belt passing between the bails 33 and 35 and in front of said bail 33 and being preferably threaded through a loop 39 which is mounted upon the first mentioned end portion of the belt. In this manner, the belt may be adjusted about the body of the wearer of the garment so as to suitably close the front of the garment and adapt the 45 waist portion of the garment about the waist of the wearer, and it will be evident that the fly flap 15 will first be arranged substantially flat against the abdomen in the position shown in Figure 2 of the drawings, before the end portion 37 of the truss belt is fitted through the buckle. It will likewise be observed by reference to Figures 1 and 2 of the drawings, that the forward stretches of the truss belt extend slightly downwardly 50 to conform to the slight downward curvature of the upper edge portion 6 of the waist of the garment and to better support and sustain the abdomen. The tab 21 heretofore described is adapted to engage over the 55 upper edges 6 of the waist portion of the garment and likewise over the truss belt 25, as most clearly shown in Figures 1 and 5 of the drawings, so that in this manner, the fly flap 15 is supported against any sagging 60 and, therefore, is maintained in the flat position in which it was initially arranged and in which position, as will be observed by reference to Figures 1, 2 and 4 of the drawings, it extends completely across and closes 65 the fly opening. It will be further observed that the tab has one side engaged with the buckle in order to prevent rumpling of the fly flap 15.

From the foregoing description of the invention it will be evident that a garment constructed in accordance with the principles thereof will be exceptionally comfortable to wear, particularly in view of the provision of the fly flap 15 which completely 70 closes the fly without the employment of buttons, and likewise particularly in view of the arrangement of the truss belt 25, which is such as to insure of firm and yet comfortable support of the abdomen so as to tend to prevent rupture and to likewise prevent any 75 pains incident to violent exercise. It will also be evident that there is no likelihood of displacement or disarrangement of the fly flap with respect to the fly opening in view 80

of the engagement of the tab 21 over the upper edge of the front portion of the garment at the opposite side of the fly opening and over the upper edge of the front portion of the said truss belt. Of course, any suitable construction of buckle may be substituted for the one shown in the drawings and hereinbefore described, but the buckle illustrated and described is preferred as it

10 may be completely removed from the belt before the garment is sent to the laundry.

Having thus described the invention, what I claim is:

15 A pair of drawers having a fly opening at the front extending upwardly from the crotch portion of the drawers, a flap at one

side to the front of the drawers laterally offset beyond the corresponding side of the fly opening, said flap being disposable to completely span the said opening from top to 20 bottom, a belt having a terminal fastener, said belt extending about the waist of the drawers and constituting means for supporting the drawers upon the wearer, a downturned tab upon the upper edge of the 25 fly flap for engagement with the belt to prevent sagging of said flap, said tab being engaged at one side with the terminal fastener.

In testimony whereof I affix my signature.

ANDREW P. PAZOWSKI. [L.S.]
